Primary Examiner — Samantha Wood*Assistant Examiner* — Emily A Caven(74) *Attorney, Agent, or Firm* — BEKIARES ELIEZER LLP(57) **CLAIM**

The ornamental design for a pet hair dryer attachment, as shown and described.

DESCRIPTION

FIG. 1 is a bottom isometric view of the pet hair dryer attachment;

FIG. 2 is a top isometric view thereof;

FIG. 3 is a bottom view thereof;

FIG. 4 is a top view thereof;

FIG. 5 is a left elevation view thereof;

FIG. 6 is a right elevation view thereof;

FIG. 7 is a back elevation view thereof; and,

FIG. 8 is a front elevation view thereof.

The broken lines illustrate portions of the pet hair dryer attachment that do not form a part of the claimed design.
